PATENTED MAY 5, 1903.

W. L. E. KEUFFEL.

SURVEYOR'S ROD.

APPLICATION FILED OCT. 4, 1902.

NO MODEL.

UNITED STATES PATENT OFFICE.

WILLIE L. E. KEUFFEL, OF HOBOKEN, NEW JERSEY, ASSIGNOR TO THE KEUFFEL & ESSER COMPANY, A CORPORATION OF NEW JERSEY.

SURVEYOR'S ROD.

SPECIFICATION forming part of Letters Patent No. 727,151, dated May 5, 1903.

Application filed October 4, 1902. Serial No. 125,886. (No model.)

To all whom it may concern:

Be it known that I, WILLIE L. E. KEUFFEL, a citizen of the United States, and a resident of the city of Hoboken, in the county of Hudson and State of New Jersey, have invented certain new and useful Improvements in Surveyors' Rods, of which the following is a specification.

This invention relates to certain improvements in that class of surveyors' rods constructed of a plurality of relatively adjustable sections whereby the rod may be extended as required in use or folded for convenience in carrying or transporting the same.

The invention consists in certain peculiarities of construction, substantially as hereinafter described, and particularly set forth in the subjoined claims.

The general object of the invention is to provide a rod, comprising a series of telescoping or sliding sections having means whereby when all the sections are extended and the sections clamped together one long rod is the result and with means for clamping the sections together, whereby each section may be moved with respect to its adjacent section and clamped at any point, which will be of most simple, durable, and practical construction and be most easily and readily extended or contracted; and an especial object of the invention is to provide a rod of the type stated which provides for the employment of three sections without requiring that any of the same, including the third or uppermost one, be mounted in a groove formed in the wood of either of the other sections. In other words, the particular object of the invention is to provide a surveyor's rod having a maximum range of extensibility which will be of light weight and simple construction and avoid the liability of sticking and wobbling of the sections when the wood swells and shrinks, which is always present when any of the sections are set in grooves cut in another section.

In the drawings, Figure 1 is a front plan view of the rod broken away at a portion of its length and with the sections only slightly extended. Fig. 2 is a side elevation thereof

looking from the right. Fig. 3 is a side elevation thereof looking from the left. Fig. 4 is a rear plan view thereof. Fig. 5 is a side elevation of the connections between one pair of rod-sections. Fig. 6 is a side elevation of the connections between another pair of the rod-sections. Fig. 7 is a transverse section through one of the clamps.

In the drawings, 1 is the front section of the rod, provided at its bottom with a rearwardly-extending foot-piece 11 and terminating in a U-shaped shoe 12, secured to the said foot-piece by suitable means, as screws 13 13. Its vertical sides 14 14 extend slightly in front of its graduated face 15, thus affording bearings for the flanges 52 of the sliding clamp 5, connecting it to the middle section 2 of the rod. At its top it is provided on each side with U-shaped guides 16 16, each firmly secured to one of the vertical sides 14 14 and projecting rearwardly beyond the same to engage longitudinal grooves 22 in the vertical sides 24 of the middle section 2. It is also provided with a stop 17, adapted to abut against a lug 26, secured to the middle section 2, whereby the further upward motion of the latter is prevented.

The middle section 2 of the rod is provided at its bottom with a rearwardly-extending foot-piece 21, adapted to abut against the upper surface 18 of the foot-piece 11 of the front section 1. It is longitudinally grooved at 22 to receive the flanges of the clamp 6, securing it to the rear section 3 and the U-shaped guides 16. At its top it is provided with a U-shaped strap 23, firmly secured to its vertical sides 24 and projecting rearwardly beyond it, encircling the rear section 3. Its vertical sides 24 project slightly in front of its graduated face 25. On one side it is provided with a lug 26, adapted to be brought in contact with the stop 17 on section 1, as above stated.

The rear section 3 is adapted to pass between the rear closed portion of the U-shaped strap 23 and the rear of the middle section 2. It is provided at its top with a similar U-shaped strap 31, adapted to rest upon the upper edge of the strap 23 when section 3 is in its lowest position, and on one of its sides is

placed a stop-lug 32, which being brought into contact with the lower edge of the strap 23 prevents the further upward movement of this section.

5 Particular attention is called to the fact that neither the third section 3 nor any of the other sections of the rod are set in a groove formed in an adjacent section and that the connection of the several sections with each other is such that the swelling or shrinking of the wood under the influence of climatic conditions will not cause any of the sections either to bind or be loose, whereby a fruitful source of trouble experienced with this type 15 of rod is eliminated.

The clamp 5, (shown in section in Fig. 7,) securing the connection between the sections 1 and 2, consists of a U-shaped strap 51, provided with flanges 52, which lap over and engage the vertical sides 14 14 of section 1. The transverse member of the strap is provided with a threaded yoke 53, adapted to receive a thumb-screw 54, the rotation of which tends to press its point against the rear of the foot-piece 21, and thus clamp it to the section 1. Two guide-posts encircled by coiled springs 55 serve to maintain a constant tension between the flanges 52 and sides 14 14 and prevent slipping. The clamp 6 is of the same 30 construction.

By reason of the above construction I can make a rod of the usual length of a surveyor's rod when extended, but one which will close up to about four feet four inches, which 35 makes it very compact and overcomes the objections of having a long rod difficult to carry through woods and brush or too long to carry into a street or railroad car.

Having described my invention, what I 40 claim as new is—

1. A surveyor's rod composed of three sections of which the lower and upper ones are located at opposite faces of the middle section, said middle section having its opposite 45 sides grooved longitudinally, guiding means projecting from the lower section and engaging said grooves and a clamping and releasing means carried by the upper section and also engaged with said grooves.

50 2. A surveyor's rod composed of three sections of which the lower and upper ones are located on the opposite faces of the middle section, said middle section having longitudinally-grooved sides, means adjustable to clamp the lower and middle sections together, a guiding means at the upper end of the lower section having laterally-bent ends which take 55 into said grooves in the middle section, a clamp for securing the upper section adjustably to said middle section said clamp having flanges engaging the grooves in said middle section, and a guide projecting from said middle section and engaging said upper section.

65 3. The combination in a surveyor's rod of a plurality of sections, and means for adjustably connecting any two adjacent sections and se-

curing them in place after adjustment, consisting of clamps comprising straps mounted upon one section and adapted to encircle projecting portions of the other section, the straps being tightened by means of thumb-screws and provided with means for maintaining a constant but yielding connection between the two sections. 70

4. The combination, in a surveyor's rod, of a plurality of sections, and means for adjustably connecting any two adjacent sections and securing them in place after adjustment, embracing a clamp having a strap mounted 80 upon one section and having projecting portions engaged with the other section, a tightening-screw and interposed spring, substantially as described. 75

5. The combination, in a surveyor's rod, of 85 a plurality of relatively adjustable sections one of which has longitudinally-grooved sides, guiding means carried by one section and having ends projecting into said grooves, and a clamp having ends projecting into said 90 grooves and also having a tightening-screw.

6. The combination, in a surveyor's rod, of 95 a plurality of relatively adjustable sections, one of which has longitudinally-grooved sides, guiding means carried by one section and 100 having ends projecting into said groove, and a clamp having ends projecting into said grooves and also having a tightening-screw and an interposed spring.

7. The combination, in a surveyor's rod, of 100 a plurality of relatively adjustable sections mounted one upon the other and each having a laterally-projecting lower end, one of said sections having longitudinally-grooved sides, straps projecting from one section and having 105 flanges engaging the grooves of the other section, and a clamp for securing said sections in relatively adjusted position, said clamp comprising a U-shaped strap having flanges 110 engaged with one section and a tightening-screw which bears against the laterally-projecting lower end of the other section.

8. The combination, in a surveyor's rod, of 115 a plurality of relatively adjustable sections mounted one upon the other and each having 120 a laterally-projecting lower end, one of said sections having longitudinally-grooved sides, straps projecting from one section and having flanges engaging the grooves of the other section, and a clamp for securing said sections 125 in relatively adjusted position, said clamp comprising a U-shaped strap having flanges engaged with one section, a tightening-screw carried by the closed end of said strap and bearing against the laterally-projecting lower end of the adjustable section, posts between the closed end of said strap and said laterally-projecting ends, and springs on said posts.

9. The combination, in a surveyor's rod, of 130 three relatively adjustable sections the upper and lower of which are mounted on opposite faces of a middle section, said middle section having longitudinally-grooved sides, a clamp for securing the middle section adjustably on

the lower section, guide means for the middle section, projecting from the lower section, and having projecting flanges engaging said grooves, a clamp securing said middle section and upper section adjustably together, said clamp having projecting flanges engaging said grooves in the middle section, a guide-strap secured to the upper end of the middle section and engaging said upper section, and

stops for limiting the adjustments of the several sections.

Witness my hand this 29th day of September, 1902, at the city of New York, in the county and State of New York.

WILLIE L. E. KEUFFEL.
